UNITED STATES PATENT OFFICE.

ROBERT MELDRUM, OF KIRKLISTON, SCOTLAND.

PORTABLE BOILER OR HEATER.

SPECIFICATION forming part of Letters Patent No. 741,266, dated October 13, 1903.

Application filed August 19, 1902. Serial No. 120,200. (No model.)

To all whom it may concern:

Be it known that I, ROBERT MELDRUM, a subject of the King of Great Britain, residing at Kirkliston, in the county of Linlithgow, 5 Scotland, have invented certain new and useful Improvements in Portable Boilers or Heaters, of which the following is a full and complete specification, such as will enable those skilled in the art to which it appertains to 10 make and use the same.

The object of this invention is to provide an improved portable boiler or heater for use in heating liquids, pitch, resin, and similar substances, a further object being to simplify the 15 construction of boilers of this class and to render the same more effective and practical, a further object being to provide a boiler or heater of the class specified with an oil furnace or burner and to avoid the smoke products from burners and furnaces of ordinary 20 type and to adapt the same for use either within or without a building and to make the same lighter and more durable; and with these and other objects in view the invention consists in a portable boiler or heater constructed 25 as hereinafter described and claimed.

The invention is fully disclosed in the following specification, of which the accompanying drawings form a part, in which the separating 30 parts of my improvement are designated by suitable reference characters in each of the views, and in which—

Figure 1 is a side elevation of a portable boiler or heater constructed according to my 35 invention; Fig. 2, a vertical section on the line 2 2 of Fig. 4; Fig. 3, a vertical section on the line 3 3 of Fig. 4; Fig. 4, a transverse section on the line 2 2 of Figs. 1 and 2; and Fig. 5, a view similar to Fig. 2, but showing a modification.

In the practice of my invention I provide a casing *a*, which is shown in the drawings as cylindrical in form, but which may be of any desired shape or form. The casing *a* is open 45 at the top and is provided in one side thereof with an opening *a*², which in the form of construction shown is closed by a plate or door *b*, held in place by vertically-arranged keepers *b*² and a bottom keeper *b*³, secured to the 50 casing *a*. The connection of the door *b* with the casing *a*, however, may be made in any de-

sired manner, and the said door is preferably made more convex than the wall of the furnace, so as to admit air at the top, or a central register *b*⁴ for the admission of air may 55 be provided, if desired. Within the casing *a* is placed a supplemental or furnace casing *c*, which in the form of construction shown is provided with a top flange *c*², which rests on a corresponding flange *a*³ at the top of the 60 casing *a* and is preferably secured thereto by bolts or screws *c*³ or in any desired manner, or the supplemental furnace may simply rest on the casing *a*.

The supplemental or furnace casing *c* is 65 tapered downwardly and inwardly, the lower end thereof being substantially less in size or diameter than the casing *a* while the upper end of the casing *c* is substantially as large as the upper end of the casing *a* and said casing *c* also shorter than the casing *a*, and by means of this construction a chamber *d* is formed in the casing *a*, which incloses the casing *c* and extends upwardly around the sides thereof to the top thereof. 75

The openings *a*² and *c*² in the adjacent sides of the casings *a* and *c* are inclosed by casing *d*² of any desired construction, and this casing may be formed integrally with the parts *a* and *c* or be formed separately and secured 80 thereto, and by means thereof the chamber *d* is closed at all points from the openings *c*⁴ and *a*².

Within the top of the casing *c* is placed a pot or kettle *e*, having a flange *e*², which rests 85 on the top of the flange *c*² of the casing *c* and is preferably secured thereto by the bolts or screws *c*³, and the pot or kettle *e* is provided with a cover *e*³, which may be connected therewith in any desired manner or be made simply 90 so as to rest thereon.

Within the casing *c* is a partition or diaphragm *c*⁵, having a slot or opening *c*⁶, which extends to the opening *c*⁴, and by means of this diaphragm or partition *c*⁵ a chamber *c*⁷ is 95 formed in the bottom of the casing *c*, which is adapted to receive an oil-reservoir *f*, which may be inserted through the openings *a*² and *c*² and which is provided with burners or burner-tubes *f*², which extend up through the 100 slot or opening *c*⁶ in the diaphragm or partition *c*⁵, and the said reservoir *f* and burner-

- tubes or burners f^2 constitute an oil-burning device or apparatus for the heating of my improved portable boiler or heater.
- It will be observed that the partition c^5 actually forms the bottom of the chamber in which the kettle e is placed, while that part of the casing c on which the reservoir is placed forms only a support for said reservoir.
- 10 The pot or kettle e is preferably provided in the bottom thereof with a draw-off pipe g , which extends outwardly through the casings c and a and which is provided with a faucet g^2 , and the top portion of the casing a is provided with a tube h , through which the chamber d may be filled, and the bottom of said casing is provided with a draw-off tube or pipe h^2 , through which the contents of said chamber d may be exhausted.
- 15 In practice in heating liquids both the pot or kettle e and chamber d are filled with the liquid to be heated, and while the contents of the pot or kettle e are being heated to the desired extent the contents of the chamber d are also being heated, or partially so, and when the contents of the pot or kettle e have been heated to the desired extent the said pot or kettle may be emptied and the contents of the chamber d be drawn out and placed in the pot 25 or kettle e and said chamber d may be refilled, and by means of this construction and operation all the heat of the furnace is utilized, as will be readily understood, there being no heat lost by radiation, thus saving time and fuel.
- 30 In using my improved boiler or heater for melting pitch, resin, and like substances the said substances are placed in the pot or kettle e , and in this case liquids may be heated at the same time, if desired, in the chamber d , and if said chamber is not devoted to this use it will serve to prevent radiation, and thus conserving the heat generated in the furnace-chamber by the burner or burners placed therein.
- 35 A boiler or heater constructed in this way may be made of much lighter material than when coal or wood is used as a fuel, and the said boiler or heater may be made of any desired shape—oblong, cylindrical, or square in cross-section—and if made oblong any desired number of furnace-chambers may be employed, it being understood that any suitable oil burner and supply device may be employed, that which is herein shown and described being only to indicate such devices.
- 40 In Fig. 5 of the drawings I have shown a modification in which the casing a is provided at about one-third of the distance from the bottom thereof with a partition-plate k , having a central opening k^2 and forming a compartment k^3 in the bottom of said casing. The compartment k^3 is provided at one side with an opening k^4 , similar to the opening a^2 in Fig. 4, and this opening is closed by any suitable door k^5 . In this form of construction a supplemental inner casing m is employed having a top flange or rim m^2 , which
- rests on the flange or rim a^3 of the casing a and on which is supported a kettle e , which is provided with the cover e^3 , these parts being exactly the same as those shown in Figs. 1 to 3. In this form of construction the supplemental casing m is tapered inwardly and downwardly, as in Fig. 2, but the bottom thereof is secured to partition-plate k so as to form an annular chamber n between said supplemental casing and the outer casing a , and this chamber is of greater transverse dimensions at the bottom than at the top, and in practice the said chamber is designed to receive liquids which may be placed therein through a pipe o and withdrawn therefrom through a faucet o^2 . Within the bottom chamber k^3 is placed the oil-reservoir f , having burner-tubes f^2 , the same as the construction shown in Fig. 2. These burner-tubes pass upwardly through the central opening k^2 in the partition-plate k and around the top of the apparatus, and preferably in the top flange or member of the kettle e is formed escape-passages p for the products of combustion, as shown in Figs. 1 and 5.
- 45 Any suitable means may be provided for admitting air into the chamber k^3 and in the operation of this form of construction substantially the same as has been hereinbefore described with reference to the construction shown in Figs. 1 to 3.
- Having fully described my invention, what I claim as new, and desire to secure by Letters Patent, is—
1. A portable furnace or heater, comprising a main outer casing open at the top, a supplemental casing placed therein and supported at the top thereof, said supplemental casing being open at the top and being tapered downwardly and inwardly and being shorter than the main outer casing whereby a chamber is formed in said main outer casing which encloses the supplemental casing, said main and supplemental casings being also provided in their adjacent sides and at the bottom of the supplemental casing with openings which are closed or cut off from said chamber, and through which a furnace-burner may be passed into the supplemental casing, and a pot or kettle placed in the top of the supplemental casing and supported thereon, substantially as shown and described.
2. A portable furnace or heater, comprising a main outer casing open at the top, a supplemental casing placed therein and supported on the top thereof, said supplemental casing being open at the top and being tapered downwardly and inwardly and being shorter than the main outer casing whereby a chamber is formed in said main outer casing which encloses the supplemental casing, said main and supplemental casings being also provided in their adjacent sides and at the bottom of the supplemental casing with openings which are closed or cut off from said chamber, and through which a furnace-burner may be passed into the supplemental casing, and a

pot or kettle placed in the top of the supplemental casing and supported thereon, said supplemental casing being also provided with a transverse partition, substantially as shown 5 and described.

3. In a portable furnace or heater, a main outer casing open at the top, a supplemental inner casing supported therein, and also open at the top and the walls of which are tapered 10 inwardly and downwardly so that the bottom thereof is of less dimensions than the corresponding part of the main outer casing, and the bottom of which is also provided with an

opening, a kettle within the top of the supplemental casing, and suspended thereon, and 15 a removable burner supported beneath the bottom of the chamber in which said kettle is placed substantially as shown and described.

In testimony that I claim the foregoing as my invention I have signed my name, in presence of the subscribing witnesses, this 5th day of August, 1902.

ROBERT MELDRUM. [L. S.]
